United States Patent Office.

E. B. SCATTERGOOD, OF ST. JOHNS, MICHIGAN.

Letters Patent No. 100,808, dated March 15, 1870; antedated March 11, 1870.

IMPROVED WASHING-MACHINE.

The Schedule referred to in these Letters Patent and making part of the same.

To whom it may concern:

Be it known that I, E. B. SCATTERGOOD, of St. Johns, in the county of Clinton, and State of Michigan, have invented a new and useful Improvement in Washing-Machines; and I do declare that the following is a true and accurate description thereof, reference being had to the accompanying drawings and to the letters of reference marked thereon, and being a part of this specification.

The nature of this invention relates to an improvement in the construction of that class of machines employed in cleansing textile fabrics; and consists in a tub or box of any desired form, within which is fitted a receptacle for the fabrics, which is made of non-corroding wire-cloth, or its equivalent, sustained upon springs of any desired form, and which should also be made of non-corroding material, such as galvanized iron, or its equivalent, and any suitable pounder, operated vertically by any desired power.

In the drawings, which are in vertical section—

A represents any suitable tub or box made watertight, and of any desired form.

B are springs, made of any proper non-corroding material, which rest upon the bottom of the tub A, and support the basket C, which should be made to conform to the shape of the tub A of wire-cloth of a coarse mesh, and should also be constructed of non-

corroding material. This basket is intended as a receptacle for the clothes to be cleansed.

D is a pounder-head attached to the lower end of the handle E or shaft, to which a vertically-reciprocating motion may be communicated by any desired power.

If convenient and more preferable, the springs B may be secured in a frame, F, which should be placed in the bottom of the tub.

The various parts being in place, as described, the necessary water being in the tub, the clothes should be placed in the basket, when the pounder should be operated in the usual way. Every downward motion of the pounder forces the clothes under the water by compressing the springs, while the expansion of the same will elevate them upon the upward stroke of the pounder. The further operation of this device is so simple that a more full description is deemed unnecessary.

What I claim as my invention, and desire to secure by Letters Patent, is—

The wire basket C, supported by the springs B, in combination with the tub A, and pounder E, when constructed and arranged to operate as herein described.

E. B. SCATTERGOOD.
